COMBINATION PAN AND MOP SQUEEZING TRAY FOR WAX OR THE LIKE

Joseph P. Dumit, 6242 N. Lenox, Chicago, Ill.

Filed Dec. 6, 1962, Ser. No. 72,750

Term of patent 14 years

(Cl. D9—2)

Fig. 1.

Fig. 2.

Fig. 3.

FIG. 1, is a perspective view of a combination pan and mop squeezing tray for wax or the like showing my new design, the rear side being substantially the same;

FIG. 2, is a top plan view of the same;

FIG. 3, is a side elevational view thereof, the opposite side being substantially the same.

I claim:

The ornamental design for a combination pan and mop squeezing tray for wax or the like, as shown and described.
